CLAIM

The ornamental design for a fluid-dispensing container, as shown and described.

DESCRIPTION

FIG. 1 is a side view of the fluid-dispensing container showing my new and ornamental design, the opposite side being a mirror-image thereof;

FIG. 2 is a front view from the pouring side thereof;

FIG. 3 is a rear view from the handle side thereof;

FIG. 4 is a top plan view thereof; and,

FIG. 5 is a bottom plan view thereof.

FIG.1

FIG.4
